MONROE SUNSHINE, OF NEW YORK, N. Y.

GARMENT-PRESSING MACHINE.

1,070,680.

Specification of Letters Patent.

Patented Aug. 19, 1913.

Application filed May 23, 1911. Serial No. 628,981.

To all whom it may concern:

Be it known that we, ERNEST M. GLASCO, a subject of the Crown of Great Britain, and MONROE SUNSHINE, a citizen of the 5 United States, and residents of the borough of Manhattan, in the city and State of New York, have invented a new and useful Improvement in Garment-Pressing Machines, of which the following is a specification.

10 Our invention relates to garment pressing machines and has for its object to provide novel means whereby the pressing iron may subject the work to great pressure with a minimum amount of movement of the foot 15 lever, a power multiplying mechanism being introduced between the lever and the iron carrying plunger for accomplishing the result above stated.

A practical embodiment of the invention 20 is represented in the accompanying drawings, in which,

Figure 1 represents a machine embodying our improvement, the machine being shown in vertical section with the parts in the position which they assume when the foot lever 25 has been depressed to the limit of its movement. Fig. 2 is a detail sectional view similar to Fig. 1, with the parts in the position which they assume when the foot lever is at 30 the limit of its upward movement, and Figs. 3, 4 and 5 are diagrams showing the first and intermediate and the final position of the power multiplying connection between the foot lever and plunger.

35 A suitable frame 1 forms a support for the work-table 2, the plunger bracket 3 and the foot lever 4. The presser iron 5 is carried by an extensible member 6 of the presser arm 7, which presser arm is hinged at 8 to a 40 collar 9 carried by the plunger 10. This plunger 10 is fitted to reciprocate vertically in upper and lower bearings 11, 12, of the bracket 3. Diagonal tension rods 13 (one of which is shown in the accompanying drawings) connect the outer end of the presser arm 7 with a collar 14 fixed to the plunger 10 intermediate the upper and lower bearings 11, 12 of the bracket 3. The foot lever 4 is hinged at 15 to the frame 1, at a point 45 below the plunger 10. A hanger 16 is secured to the lower end of the plunger 10 and an uprising rock arm 17 is pivoted at 18 to the hanger 16. An inner rod 19 is pivotally attached at 20, to the rock arm 17, adjacent to its axis 18, and is pivotally attached

5 to 21 to the foot lever 4, adjacent to its axis 15. An outer rod 22 is pivotally attached at 23, to the rock arm 17 at a point beyond the point of attachment 20 of the inner rod 19, and is pivotally attached at 24 to the foot 60 lever 4 at a point beyond the point of attachment 21 of the inner rod 19 thereto. The point of attachment 20 of the inner rod 19 to the rock arm 17 is at a point to the rear of a line drawn through the axis 18 of said arm 65 17 and the point of attachment 23 of the outer rod 22 thereto. A spring 25 serves to automatically return the plunger 10 and foot lever 4 to their normal raised position, which spring is attached to a lug 26 on the bearing 70 12 of the bracket 3, and to a lug 27 on the hanger 16.

A spring cushion is attached to the frame in position to be struck by the foot lever 4 as it approaches the limit of its upward 75 movement, for cushioning the blow, which cushion is herein shown as comprising a plunger 28 having a collar 29 fixed thereto between which collar and an abutment 30 is interposed a cushioning spring 31. 80

In operation, presupposing the parts to be in the position shown in Figs. 2 and 3, as the foot lever 4 is depressed by the operator, the plunger 10 will be drawn down at a constantly decreasing speed because 85 of the double rod connection between the rock arm 17 and the foot lever 4. The points of connection at the upper ends of the rods 19 and 22 with the rock lever 17, are so arranged that the depression of the 90 lever 4 will cause the rod 22 to swing the point of connection 20 of the rod 19 with the lever 17, toward a position above the axis of the said rock lever 17. As this point 20 approaches its position above the axis 18, the downward movement of the plunger 10 grows less and less, while the power of the operator is increased owing to the shifting 95 of the pull from the point 24 entirely to the point 21 on the lever 4 adjacent to the axis 15 of the lever. It will thus be seen that a novel power multiplying connection is provided between the lever 4 and the plunger 10, which connection will permit a comparatively rapid downward movement of the plunger and thereby the pressing iron during that part of the stroke where the iron is doing no work and a very slow and powerful movement during that part of the stroke 100 where the iron is doing its work. A fur-

ther advantageous feature is the hinging of the presser arm 7 to the plunger and the provision of the diagonal tension rods 13 so that the arm is relieved of any breaking strain thereon and the said rods serving to receive the said strain instead.

What we claim is:

1. In a garment pressing machine, a vertically reciprocating plunger, a foot lever 10 for depressing said plunger, means for automatically returning said plunger and foot lever to their normal raised position and a power multiplying connection between the foot lever and plunger comprising an up- 15 rising rock arm pivoted to the plunger, and inner and outer connecting rods leading from points on the foot lever at different distances from its axis to points on the rock arm at different distances from its axis.
2. In a garment pressing machine, a vertically reciprocating plunger, a foot lever 20 for depressing said plunger, means for automatically returning said plunger and foot

lever to their normal raised position and a power multiplying connection between the 25 foot lever and plunger comprising an up- rising rock arm pivoted to the plunger, inner and outer connecting rods leading from points on the foot lever at different distances from its axis to points on the rock 30 arm at different distances from its axis, the points of attachment of the connecting rods to the rock arm being such that as the foot lever is depressed the point of attachment of the inner rod to the rock arm is moved into 35 position over the axis of said rock arm.

In testimony, that we claim the foregoing as our invention we have signed our names in presence of two witnesses, this first day of May, 1911.

ERNEST M. GLASGOW,
MONROE SUNSHINE.
